United States Patent Office

Des. 228,720
Patented Oct. 23, 1973

228,720

PLAQUE

Raymond Stephen Cowan, R.R. 1, Highway 7,
Unionville, Ontario, Canada

Filed Mar. 8, 1971, Ser. No. 122,271

Claims priority, application Canada Jan. 22, 1971

Term of patent 14 years

Int. Cl. D6—07

U.S. Cl. D6—244

FIG. 1

FIG. 4

FIG. 3

FIG. 2

FIG. 1 is a front perspective view of a plaque showing my new design;

FIG. 2 is a front elevational view thereof on a reduced scale;

FIG. 3 is a side elevational view thereof; and

FIG. 4 a sectional view taken on the line 4—4 of FIG. 2.

I claim:

The ornamental design for a plaque, as shown.
